UNITED STATES PATENT OFFICE.

ALBERT H. DANFORTH, OF MONSON, MASSACHUSETTS.

FOLDING STAGING-BRACKET.

SPECIFICATION forming part of Letters Patent No. 650,707, dated May 29, 1900.

Application filed January 13, 1900. Serial No. 1,267. (No model.)

To all whom it may concern:

Be it known that I, ALBERT H. DANFORTH, a citizen of the United States of America, residing in Monson, in the county of Hampden 5 and State of Massachusetts, (whose post-office address is Monson, Massachusetts,) have invented new and useful Improvements in Folding Staging-Brackets and Supporting-Bars for the Same, of which the following is a specification, reference being had to the accompanying drawings and to letters of reference marked thereon.

My invention relates to brackets adapted for supporting temporary stagings as employed for the erection and repair of buildings, and more especially relates to folding brackets of the type referred to, my object being to provide a folding bracket which shall be of simple construction, light weight, easily 20 operated, inexpensive in cost of manufacture, convenient to place in position, firm in its support, and which when not in use may all be easily and expeditiously packed and folded together, so as to occupy but little space, thus 25 rendering it convenient to handle, transfer, and store.

The invention sought to be protected by this application relates more especially to the supporting-bar through which the supporting-rod is projected, and which bar takes the strain of the bracket when in use and is so shaped as to be packed between the top bar and the brace of the bracket, they being shaped, either one or both, to rest in the channel formed in the supporting-bar.

In the accompanying drawings, in which like letters of reference indicate like parts, Figure 1 is a perspective view of my improved folding bracket, the same being shown in its 40 extended or open position with the supporting-bar in position as occupied when the bracket is in use for supporting a staging. Fig. 2 is a perspective view of the same when folded, the supporting-bar being shown 45 clamped between the top bar and brace of the bracket, and Fig. 3 is a front view of the supporting-bar.

The construction and operation of my device will be readily understood upon reference to the drawings in connection herewith.

The bracket is constructed substantially as illustrated in United States Letters Patent

issued to me March 22, 1899, and numbered 600,858. The thickness of the top bar *a* or of the brace *b* are for at least a portion of their 55 distance no greater than the width of the channel in the supporting-bar *i*, so that when the bracket is folded for storage, transportation, &c., the supporting-bar extends over either the top bars *a* or the brace *b*, as illustrated, 60 for instance, in Fig. 2 of the drawings, thus effectually securing it in place while the bracket is folded, and while it occupies but trivial space all danger of displacement or loss is avoided.

In the construction of buildings and in substantially all the buildings already constructed the studding is set sixteen inches from center to center, so that I prefer that the supporting-bar be made of a length of twenty 70 inches at least, thus giving it ample bearing at each end upon the studding, and to enable the user to save the time required to measure with some degree of accuracy to locate the position of the hole for the supporting-rod *g* through the boarding to bring the rod *g* in registry with a central opening in the supporting-bar *i*. I provide the bar with several openings of sufficient size to receive the holding-rod, and if for illustration the bar *i* 75 be provided with three openings, one in the center and one at each side of the central opening and of a distance therefrom of four and one-half inches, it will be seen that the hole through the boarding for the passage of 80 the supporting-rod *g* may be made at any point adjacent to the center line between the studding and the bar *i* may be moved in one or the other direction, so as to bring one of the openings in registry with the holding-rod, 85 and at the same time the supporting-bar will bear at both ends against the studding, so that by providing a multiplicity of openings in the supporting-bar much time is saved in 90 measurements to determine the location of the opening to be made through the boarding in order to have the bracket properly supported.

The holding-bar is channeled and is made of iron and may be U-shaped or of any other 100 convenient shape in cross-section provided there are depending flanges or side parts which will set over one of the main parts of the bracket, and thus avoid danger of lateral

- displacement when it is so located. Of course if the supporting-bar be made of sufficient thickness and provided with a plurality of holes and be provided with depending lips or parts at the sides, so as to prevent lateral displacement when it is "stored" in the folded bracket, the result may be satisfactory; but a lighter and better device is formed from channel-iron.
- 10 Having therefore described my invention, what I claim, and desire to secure by Letters Patent, is—
- 15 1. In combination with a folding bracket, a supporting-rod projecting rearwardly therefrom, and a channeled supporting-bar provided with a plurality of openings in the back thereof for the passage of the supporting-rod and having a channel of a width as great as the thickness of one of the bracket-bars, substantially as and for the purposes shown.
- 20 2. In combination with a folding bracket,

a channeled supporting-bar having one or more openings to receive the rod of the bracket, the bracket having a part of no greater thickness than the width of the channel in the supporting-bar, substantially as shown. 25

3. The combination of a bracket capable of folding one part against another, a channeled supporting-bar, the channel being of a width not less than the thickness of one of the bars of the bracket, substantially as shown. 30

4. The combination of a bracket capable of folding one part against another, a supporting rod and bar the latter being provided with openings to receive the supporting-rod, 35 and with depending side pieces to set over one of the bracket-bars proper, substantially as shown.

ALBERT H. DANFORTH.
